UNITED STATES PATENT OFFICE.

MOSES VOLNEY LIDDELL, OF HARVEY, ILLINOIS, ASSIGNOR TO AUSTIN MANUFACTURING COMPANY, OF CHICAGO, ILLINOIS, A CORPORATION OF ILLINOIS.

DUMP-WAGON.

1,310,916.

Specification of Letters Patent. Patented July 22, 1919.

Original application filed July 24, 1918, Serial No. 246,437. Divided and this application filed October 25, 1918. Serial No. 259,644.

To all whom it may concern:

Be it known that I, MOSES VOLNEY LIDDELL, a citizen of the United States, residing at Harvey, in the county of Cook and State 5 of Illinois, have invented certain new and useful Improvements in Dump-Wagons, of which the following is a specification.

This application is a division of my application Serial No. 246,437, filed July 24, 1918.

10 The present invention relates to vehicles for receiving and transporting material in loose form or condition which adapts it to be delivered by dumping or discharging through the bottom of the receptacle, and 15 the invention finds its fullest realization in such a vehicle in which the receptacle is provided with a double hopper bottom, and particularly one in which each hopper bottom is closed by a pair of doors, the object being 20 to provide for sustaining the load incident to a comparatively large mass of material carried without undue proportions in the doors and the mechanism for working them, and without impairing prompt and 25 complete evacuation of the receptacle when the doors are opened; also to provide a single means whereby all the doors may be easily manipulated to closed position and may be instantly released at will to automatic 30 opening.

Further or incidental objects relate to the disposition of the two hopper bottoms in a manner to leave a space or archway extending intermediately through the receptacle, 35 and to locate the hinges of the dropping doors in such position that when permitted to depend the doors will form vertical continuations of the walls of the archway on the one hand, and barriers to the outward 40 discharge of material and possible impairment of the vehicle mechanism on the other hand.

The invention will be fully understood upon reference to the accompanying drawing, 45 reproduced from my original application, aforesaid, and in which—

Figures 1 and 2 are, respectively, a front elevation and a side elevation of the receptacle together with mechanism for control 50 of its doors, and the appurtenant portions of a vehicle upon which it is mounted; and Fig. 3 is a detail.

R represents the receptacle which is de-

signed more particularly to adapt it to receive sweepings from a pick-up street 55 sweeper, but which may have its form and proportions, as well as the shape of its upper part varied to adapt it to any particular use for which it may be desired. This receptacle is shown supported upon side rails F of 60 the vehicle frame through the medium of cross bars R¹⁷, R¹⁸, reinforced by supplemental frame members F³, said members F and F³ extending longitudinally of the vehicle, the receptacle being in a position to 65 depend its two bottom sections between the longitudinally extending rails, and being preferably related to the vehicle frame in a manner to truss or support the latter.

The receptacle R is provided with a 70 double hopper bottom R¹, R², developed by the internal crest R³ in a manner to leave a central tunnel or archway through which to pass other vehicle parts or connections as may be desired, and also to admit the supplemental frame F³. In the embodiment here shown, the hoppers R¹, R², are closed at bottom by the pairs of twin doors R⁴. The doors R⁴ are hinged at R⁵, and are controlled by chains R⁶ passing through the 80 thimbles R⁷ beneath the doors and having their free ends so wound upon the shaft R⁸ that the doors may be drawn tightly to their seats beneath the hoppers R¹, R² whenever the chains are wound up upon the shaft, or 85 they will be permitted to drop away from the hoppers and deposit the contents of the latter whenever the winding shaft R⁸ is released so that the chains may unwind. To bring each pair of doors under the control 90 of the chain with compensation so that both doors will be closed tightly although one door may reach its seat in advance of the other, each chain is doubled upon itself and has its middle portion anchored upon a 95 bracket R⁹ at the rear of the receptacle, the free ends of the chain R⁶ being attached to the winding shaft R⁸ in each instance. Thus the portion of the chain beneath either door may yield if the door engaged 100 by the other portion should first come to a seating and thus permit the winding action to continue until both doors are tightly closed. In order to compensate for stretching or wear in the chains of the respective 105 pairs of doors, the brackets R⁹ may be

made adjustable vertically, as, for instance, through slot and bolt connection R^{9x} (Fig. 3), so that both pairs of doors will attain the closed position simultaneously. In order to control the winding shaft R^s , it is offset from the receptacle by brackets R^{8x} secured between cross bars R^{18} and complementary rails R^{19} , and provided with a ratchet wheel R^{10} normally held against 10 winding by a dog R^{11} having spring R^{13} , and pivoted at R^{12} , while a lever R^{14} fulcrumed upon the shaft R^s and carrying a resiliently depressed hand-controlled pawl R^{15} is adapted by its normal oscillatory movement to rotate the ratchet R^{10} and shaft R^s 15 to wind up the chains, but has a toe R^{16} that encounters and unseats the dog R^{11} whenever said lever is thrown down beyond its normal range of winding movement, thereby 20 releasing the winding shaft and permitting the chains to unwind and the doors to drop, and discharge the material within the hoppers. The pawl R^{15} is positively forced to the ratchet wheel R^{10} by means of the grip 25 lever R^{14x} , and this acts upon the pawl through the medium of the spring R^{15x} with the result that motion in the grip lever R^{14x} is not necessary as the pawl trips backward over the ratchet in taking a new hold upon 30 the wheel.

From the foregoing description it will be seen that the receptacle divides its load into two parts, each readily delivered and without in any way impairing the complete evacuation of the contents; that the discharge of each portion of the load is controlled by a pair of doors having a compensating closing connection that insures tight closure of each door; that both pairs of doors are subject to a single manual control with means for insuring the seating of both pairs of doors; that the manual control exerts ample power over the closing to insure tight seating of the doors and sealing thereof against 40 escape of material; that the doors drop automatically upon mere release of the winding connections and open simultaneously to discharge the contents; and that when the doors are open they depend in position to

preserve the central archway and restrict 50 the lateral discharge of the material.

I claim:

1. A dumping sweepings receptacle having a double hopper bottom with a pair of doors for each outlet and a common closing 55 mechanism for all the doors, comprising a chain for each pair of doors, each having a fixed anchorage for an intermediate portion of its length and having its ends extending from the anchorage beneath the respective 60 doors, and a common winding shaft receiving the free ends of both chains; the chain anchorages being adjustable to insure simultaneous closing of the two pairs of doors.

2. In a dump vehicle, the combination of 65 a receptacle having a double hopper bottom providing depending discharge legs with an arch between them, a pair of doors for each depending leg, a frame comprising inner longitudinal rails extending through the arch, 70 outer longitudinal rails extending along the outer sides of the depending legs, cross bars resting upon the longitudinal rails, and means for controlling the doors, comprising a winding shaft mounted upon said 75 cross bar and extending across both depending legs, and chains connecting said winding shaft with the doors.

3. In a dump vehicle, the combination of 80 a receptacle having a pair of depending discharge legs with an arch between them, longitudinal rails extending, respectively, through the arch and along the outer side of the depending legs, a supporting cross bar resting upon the longitudinal rails and extending across one transverse wall of the 85 receptacle, a complementary cross bar carried by the said transverse wall of the receptacle above said supporting bar, brackets supported by said cross bars, a shaft mounted in said brackets and extending across both depending legs of the receptacle, chains winding upon said shaft, and doors controlled by said chains and in closing relation to the depending legs. 95

Signed at Chicago, Illinois, this 22nd day of October, 1918.

M. VOLNEY LIDDELL.
